UNITED STATES PATENT OFFICE.

WILLIAM J. HAGMAN, OF PHILADELPHIA, PENNSYLVANIA, ASSIGNOR TO NILES-BEMENT-POND COMPANY, OF JERSEY CITY, NEW JERSEY.

STEAM-HAMMER THROTTLE-GEAR.

1,034,911.

Specification of Letters Patent.

Patented Aug. 6, 1912.

Application filed September 2, 1911. Serial No. 647,427.

To all whom it may concern:

Be it known that I, WILLIAM J. HAGMAN, a citizen of the United States, residing at Philadelphia, Philadelphia county, Pennsylvania, have invented certain new and useful Improvements in Steam-Hammer Throttle-Gears, of which the following is a specification.

In most steam hammers the throttle valve is urged to closed position by a spring and is opened by the movement of a treadle and it is usual to so adjust the length of the connection between the treadle and valve that the valve will be a trifle open when the hammer is at rest and the treadle is up, the object of this being to keep the hammer warmed up while waiting on a heat. Too liberal a throttle opening under these conditions results in undesirable waste of steam.

10 In case of quick heats no warming steam need be left upon the hammer and in case of long heats the steam should be sufficient to make up for leakage and condensation in keeping the hammer warm. Furthermore, in starting up a hammer from cold condition the throttle may require re-adjustment as the hammer has worked awhile, in order to secure the desired warming conditions without undue waste of steam. In 20 most steam hammers the connecting rod or chain between the treadle and the throttle is provided with facilities, a turn-buckle or the like, by means of which such adjustments may be made, but they are inconvenient and slow. The treadle has an upward limit of motion, as determined by a fixed stop, this position representing such position of the valve as corresponds with the desired degree of trifling opening.

25 My present invention provides for a convenient and quick adjustment of the position of the treadle so that the throttle-valve may be completely closed or left open to desired degree.

30 My invention will be readily understood from the following description taken in connection with the accompanying drawing which is a side elevation of a throttle valve gear exemplifying my invention.

35 In the drawing:—1, indicates any ordinary throttle valve, suitable for steam hammer purposes: 2, the valve-lever closing the valve by upward motion: 3, a spring co-operating with the valve-lever and urging it upward to close the valve: 4, the usual

treadle by means of which the throttle is opened or permitted to close: 5, the fixed pivot of the treadle: 6, the usual connection, rod or chain, between the treadle and the throttle-lever: 7, a cam mounted on a fixed 60 pivot and adapted to engage the top of the treadle and limit, in adjustable degree, the upward movement of the treadle: 8, a notched segment to serve in retaining the cam in adjusted position: and 9, a hand-lever connected with the cam and carrying 65 detent mechanism to co-operate with the notched segment.

The cam 7 takes the place of the usual fixed stop for limiting the upward movement of the treadle.

70 Assume that with the parts in the position indicated in the drawing the throttle is open to the maximum extent required in keeping sufficient steam on the hammer while 75 it is idle, the cam thus performing the usual office of the fixed stop. If the conditions should change so that no steam for the present was needed on the hammer then the cam would be turned up and the treadle would 80 rise and completely close the throttle. The adjustment of the cam permits of the ready adjustment of the degree of throttle-opening 85 between the two extremes mentioned, namely, that of maximum warming opening and that of complete closure.

85 In the exemplification illustrated the treadle is a treadle in fact, that is, to say, worked by foot, and the hand-lever is a hand-lever in fact, but it may well be in 90 some cases the treadle itself becomes a hand-lever, and the cam-lever might also become a foot-lever. We may therefore look upon the treadle as a throttle-operating lever, regardless of whether it be worked by hand 95 or foot, and we may look upon the cam-lever as a throttle-limiting lever regardless of whether it be worked by hand or by foot, and it is also to be observed that the cam-lever may be manipulated to bring about a 100 complete closure of the valve or a limited opening of the valve without employing the foot directly upon the treadle.

105 It is to be observed that the adjustable stop formed by cam 7 does not lock the foot-lever against normal action but simply limits the degree of closure of the throttle valve. In other words, regardless of whether cam 7 has been adjusted to permit the throttle to completely close, or adjusted 110

to prevent the throttle from entirely closing, foot-lever 4 is always free for depression for the purpose of opening the throttle to permit the hammer to go into its regular work. No locking system applied to the foot-lever 4 or to the throttle to hold the throttle in some adjusted position, and requiring to be unlocked before the throttle could be given its usual opening motion 10 would answer the purpose of stop 7 which acts upon the throttle as an abutment to limit the closing motion of the throttle while leaving it free to be opened.

I claim:—

- 15 1. A steam hammer throttle gear comprising, a throttle valve, yielding means urging the valve to closed position, an adjustable stop coöperating with the throttle valve to serve in limiting its degree of closure without interfering with its capacity for being opened, and a valve operating lever having connection with the throttle valve and adapted to serve in opening it, combined substantially as set forth.
- 20 2. A steam hammer throttle gear comprising, a throttle valve, yielding means urging the valve to closed position, a valve-operating lever having connection with the valve and adapted to serve in opening it, and a stop coöperating with the valve-operating lever to prevent the complete closure

of the valve without interfering with the motion of the lever in opening the valve, combined substantially as set forth.

3. A steam hammer throttle gear comprising, a throttle valve, yielding means urging the valve to closed position, a valve-operating lever having connection with the valve and adapted to serve in opening it, a stop coöperating with the valve-operating lever to prevent the complete closure of the valve without interfering with the motion of the lever in opening the valve, and means for adjusting said stop, combined substantially as set forth.

4. A steam hammer throttle gear comprising, a throttle valve, yielding means urging the throttle valve to closed position, a valve-operating lever having connection with the valve and adapted to serve in opening it, a pivoted cam adapted to move the valve-operating lever in valve-opening direction and to limit its movement in the valve-closing direction without interfering with its movement in the valve-opening direction, means for turning said cam, and a locking device to secure the cam in adjusted position, combined substantially as set forth.

WILLIAM J. HAGMAN.
